UNITED STATES PATENT OFFICE.

JAMES BOUCEK, JAMES HALICK, AND JOSEPH TREFNEY, OF CLEVELAND, OHIO.

HOT-AIR FURNACE.

Application filed April 28, 1927. Serial No. 187,250.

This invention relates to improvements in hot air furnaces and has for an object the provision of means for supplying preheated air to the fire box of a furnace to assist 5 combustion, and thus materially reduce the consumption of fuel.

Another object of the invention is to provide a furnace wherein fresh air is admitted to be heated for distribution, novel means 10 being provided for causing the products of combustion to circulate within the furnace for the supply of heat, together with means to retard the passage of air through the furnace and cause said air to be subjected to 15 the action of the heat within and after it leaves the fire box.

Another object of the invention is the provision of a furnace which accomplishes the above and other objects by means of a 20 novel arrangement of heat conduits and passages whereby the products of combustion are caused to travel in different paths to heat the air admitted to the furnace as the air circulates around these paths, so that a 25 maximum amount of heat from the fire box is utilized.

With the above and other objects in view, the invention further includes the following 30 novel features and details of construction, to be hereinafter more fully described, illustrated in the accompanying drawings and pointed out in the appended claims.

In the drawings:-

Figure 1 is a front elevation of a furnace 35 constructed in accordance with the invention, parts being broken away and shown in section.

Figure 2 is a sectional view on the line 2-2 of Figure 1.

Figure 3 is a sectional view on the line 40 3-3 of Figure 2.

Figures 4 and 5 are horizontal sections taken respectively on the lines 4-4 and 5-5 of Figure 2.

Referring to the drawings in detail wherein like characters of reference denote corresponding parts, the reference character 9 indicates a housing which forms the outer 45 wall of the furnace and is preferably built of brick and suitable refractory material, that is, the outside walls may be of brick and the inside provided with a refractory lining.

The reference character 10 indicates the 50 fire box of the furnace beneath which is located the grate bars 11, while beneath these

grate bars is the usual ash pit 12. The ash pit door is indicated at 13 while the feed door is indicated at 14.

Extending inwardly from the front of the 60 furnace near the bottom are air inlet passages 15. These passages are controlled by dampers or doors 16, which may be adjusted to regulate the admission of air. The air 65 passages 15 extend rearwardly along opposite sides of the furnace and behind the ash pit 12, while an upwardly extending passage 17 at the rear of the ash pit communicates with a preheating chamber 18. This chamber 18 is provided with outlet 70 passages 19 which are located adjacent the grate bars 11, so that air entering the furnace through the passages 16 will travel up through the passage 17 and will circulate around the chamber 18, and will pass from 75 this chamber in a preheated state through the passages 19 and past the grate bars 11 into the fire box. The air is thus supplied to the fire box in a preheated state.

The walls 20 of the fire box are formed 80 of suitable refractory material and are relatively thin, the top and side walls being spaced from the housing 9 so as to provide an air circulating and heating chamber 21.

Extending upwardly from each corner of the fire box as shown in Figures 3 and 4 of the drawings are vertically disposed conduits 22. These conduits have their upper 85 ends in communication with a substantially H-shaped chamber 23, as shown in Figure 90 4 of the drawings. This chamber is spaced above the top wall of the fire box and is in communication with an upwardly and outwardly extending passage 26. The lower end of the passage 26 communicates with 95 the chamber 25 at a point substantially central of the latter, while the outer end of the conduit 26 is adapted to communicate with the furnace flue to carry off the smoke and other products of combustion. A baffle 100 plate 27 is located within the chamber 25 beneath the inner end of the conduit 26.

Fresh air to be heated is admitted to the 105 chamber 21 through openings 28 provided in the housing 9. The openings 28 are relatively small and are spaced entirely around the housing, so that air entering the furnace will be more evenly distributed than would be the case if the air entered through a single large opening. This air circulates 110 around and over the top of the fire box and around the conduits 22, the chamber 25 and

conduit 26 and passes outward through openings 29 provided in the top of the furnace. From this point the air may be distributed through pipes 30 in the usual or any preferred manner. The pipes 30 extend from a hood 31 which is mounted upon the top of the furnace and with which the openings 29 communicate. A smoke pipe 32 extends from the furnace and is in communication with the passage 26.

The chamber 21 is provided with a baffle wall 31 which extends inwardly around the inner face of the housing 9 and acts to retard the heated air so that the latter will more readily circulate around the fire box, conduits and passages.

The invention is susceptible of various changes in its form, proportions and minor details of construction and the right is here-
20 in reserved to make such changes as properly fall within the scope of the appended claims.

Having described the invention what is claimed is:

25 1. A furnace comprising a housing, a fire box within the housing and having its top and side walls spaced from the walls of the housing to provide an air heating chamber having communication with the atmosphere, vertically disposed conduits extending from each corner of the fire box, a horizontally disposed substantially H-shaped passage spaced above the top of the fire box and com-

municating with the vertically disposed conduits, an upwardly and outwardly centrally located conduit communicating with the H-shaped passage, and said passage and conduits being located within the heating chamber, whereby air within said chamber will circulate over and around the passage and 40 conduits before leaving the furnace.

2. A furnace comprising a housing, a fire box within the housing and having its top and side walls spaced from the walls of the housing to provide an air heating chamber 45 having communication with the atmosphere, vertically disposed conduits extending from each corner of the fire box, a horizontally disposed substantially H-shaped passage spaced above the top of the fire box and communicating with the vertically disposed conduits, an upwardly and outwardly centrally located conduit communicating with the H-shaped passage, and said passage and conduits being located within the heating 50 chamber, whereby air within said chamber will circulate over and around the passage and a baffle extending around the inside of the housing to retard the outward passage of 55 air from the heating chamber.

In testimony whereof we affix our signatures.

JAMES BOUCEK.
JAMES HALICK.
JOSEPH TREFNEY.
